UNITED STATES PATENT OFFICE.

EDWARD SCHULTZ, OF CHICAGO, ILLINOIS, ASSIGNOR TO THE NAGEL-CHASE MFG. CO.,
OF CHICAGO, ILLINOIS, A CORPORATION OF ILLINOIS.

DESIGN FOR A COMBINED FLOOR LAMP AND SMOKING STAND.

Application filed January 20, 1927. Serial No. 20,440. Term of patent 3½ years.

To all whom it may concern:

Be it known that I, EDWARD SCHULTZ, a citizen of the United States, residing at Chicago, in the county of Cook and State of Illinois, have invented a new, original, and ornamental Design for a Combined Floor Lamp and Smoking Stand, of which the following is a specification, reference being had to the accompanying drawing, forming part thereof.

The figure is a perspective view of a combined floor lamp and smoking stand showing my new design.

I claim:

The ornamental design for a combined floor lamp and smoking stand as shown.

EDWARD SCHULTZ.
